DESIGN FOR A GREASE PUMP

Carl W. Sundberg, Detroit, Mich., assignor to
Balcrank, Inc., Cincinnati, Ohio, a corporation
of Ohio

Application February 2, 1945, Serial No. 117,726

Term of patent 14 years

(Cl. D46—1)

To all whom it may concern:

Be it known that I, Carl W. Sundberg, a citizen of the United States, residing at Detroit, in the county of Wayne and State of Michigan, have invented a new, original, and ornamental Design for a Grease Pump, of which the following is a specification, reference being had to the accompanying drawing, forming a part thereof.

The figure is a perspective view of a grease pump showing my new design. The reverse side of the article not shown is substantially like the side shown in the figure.

I claim:

The ornamental design for a grease pump, substantially as shown and described.

CARL W. SUNDBERG.
